MARINE FENDER

Harry W. Bell, Seattle, Wash., assignor to Durable Mat Company, Seattle, Wash., a corporation of Washington

Application January 24, 1940, Serial No. 315,347

7 Claims. (Cl. 114—219)

The present invention relates to marine fenders of the general type shown in the patent to C. T. Lyons, No. 1,981,182, of November 20, 1934, and the general principles of which are also shown in the reissue patent to Lyons No. 18,672.

Such marine fenders are mounted, for instance, at the bow of a tugboat, to enable it to nose along a barge or a vessel. They are subjected to severe usage. As in the Lyons patents referred to above, it is my object here to make such fenders of slabs of resilient material, for instance pieces cut from discarded or worn-out tire casings, because such material has been found to serve well under such severe usage. It wears well, it is rendered non-skid to a high degree when the cut edges of the slabs are placed to define the inner and outer wear surfaces of the fender, and it affords a very considerable degree of resilience because of the rubber content, but certain drawbacks were found to exist in the form of construction disclosed in the prior patents, and it is an object of the present invention to avoid these drawbacks and disadvantages, and in particular to provide a form of construction for such fenders which will retain all their advantages, yet will make the fender stronger, longer wearing, and cheaper in first cost and as to expense over a period of time.

Fenders constructed in accordance with the Lyons Patent No. 1,981,182 were generally constructed each to the measurement of a particular vessel, for the reason that they were so strongly constructed and so slightly flexible or variable in shape that they could not conform readily to different shapes of vessels' bows and the like, nor, moreover, could they conform readily to surface irregularities such as the guards of the vessels whereon they were mounted. It is accordingly a further object of the invention to construct fenders of this general type, which will have sufficient resilience that they can accommodate themselves to a sufficient degree to such surface variations, and to variations of the form and shape of bows such as will render the fenders standardized units, to be sold for general application, rather than a product which must be built to measure for a particular installation only.

It is also an object, as has been suggested above, by simplifying the construction, and by simplifying the number and variety of fenders that have to be made, and by making given fenders applicable to various vessels, to lessen the first cost of such fenders materially.

With these and other objects in mind, as will appear hereafter, my invention comprises the novel fender construction, the principles where-

of are illustrated in the accompanying drawing, described in this specification, and will be more particularly pointed out in the claims which are found at the end of this specification.

5 In the accompanying drawing the principles of my invention have been illustrated embodied in a typical form, but various modifications in the form, character, and arrangement of the fender and of the parts thereof may be made 10 without departing from the spirit of my invention.

Figure 1 is a plan view of a vessel's stem, showing such a fender as a bow fender applied thereto.

Figure 2 is a side elevation of the same, and 15 Figure 3 is a front view of the same.

Figure 4 is a plan view showing a modified arrangement.

The present fender consists of a plurality of 20 individual slabs 1 of length of resilient material, more or less flat, and usually having somewhat greater length than breadth. As has been indicated above, such pieces are conveniently made of discarded tire casings, and their size and shape is governed by the size and shape of the 25 tire from which they are cut. They may be pieces cut from the side walls or pieces cut from the tread, and in a given fender some of the slabs may be from the side walls and some from the tread. Indeed, the individual slabs may include both side wall and tread portions. For 30 certain pudding sections the slabs may be cut entirely across the casing from bead to bead, with the beads, however, cut away, and if such sections are cut from the extremely large tires 35 of farm tractors, for instance, a very appreciable depth of pudding may be attained with a slab cut from a single tire. Otherwise, to increase the depth of the pudding, the slabs may be laid in edge-to-edge relationship, as will be pointed 40 out.

Such slabs are placed in courses, in face-to-face relationship, and since it will usually be found that no one slab has sufficient length to include the entire extent of the fender, such 45 slabs are normally placed also in end-to-end relationship, with the joints broken in adjoining courses. No particular pattern of laying, no regularity of length, is necessary or desirable. The various slabs are laid flat, or approximately so, 50 in broken courses, in the form of the desired fender, and suitable means hold them in this form. The height of the fender is immaterial, but usually about two feet. If greater height is needed several fenders are superposed.

The slabs are held together in this form, and

as a matter of fact, in constructing the fender, are threaded upon rods or similar tension members 2, which extend through the individual slabs, and through the fender, transversely to the faces of the slabs. By providing heads 3 upon the rods 2, and by providing nuts 4 and washers received upon their opposite ends, these bolts clamp together the slabs and hold them tightly in face-to-face relationship, preventing undue or appreciable separation of the faces of the slabs, and therefore preventing undue separation of the exposed edges of the slabs, which edges cooperate to define the inner and outer faces of the fender as a whole.

It is preferred that the planes of the slabs, that is, the extent of the courses, be perpendicular to the direction of principal strain, and that the tension members parallel the line of principal compression. Since such fenders sometimes contact piling which extends more or less vertically, it is preferable that the courses extend horizontally. In consequence the rods 2 extend generally vertically. These rods are spaced horizontally by desired distances, such distances being generally determined by the average length of the slabs, or by the length of the shortest such slab. Preferably the rods are spaced no farther than sufficient to permit at least two rods to be threaded through each slab, although there will be places where it is necessary to fill in with short slabs or pieces which may be threaded upon only a single rod, for it is desired that the fender be solidly constructed, without appreciable interstices between slabs, either horizontally or vertically.

A further reason why such slabs of tire casing material are desirable, in addition to their quality of resilience and elasticity, is that they incorporate layers or sheets of fabric embedded within the rubber. This fabric may be the loosely connected cord fabric, or woven fabric, or both, but since the slabs are employed in the fender with cut edges innermost and outermost, the exposed and cut fabric affords an excellent non-skid and wear-resisting medium, serving to prevent slippage of the fender relative to the tug's skin and relative to the skin of the barge, vessel, pile, stringer or what-not that it contacts. In addition the present of the tough fiber prevents undue disintegration of the exposed rubber composition by abrasion.

One of the essential features of the present invention resides in the fact that the rods 2 are totally independent of one another and unconnected, except through the slabs 1 themselves. In the fenders of the Lyons patents it was conceived that because the fender was to be subjected to severe usage it was necessary to construct it strongly, with a steel skeleton consisting of parallel rods and connecting links or heavy bars. It was found in use that such fenders, however stoutly they might be constructed, would still be broken by the stresses imposed upon them, and that, because of the limitations upon the resilience of the rubber imposed by the bars or links connecting the rods, the fender was not sufficiently resilient, or at least was not resilient to the full extent that might be expected, due to the rubber content.

Rubber, when compressed, must flow, and when it is not permitted to flow, it loses its resilience. Moreover, if it is compressed along a vertical line and tends to flow horizontally (the tight clamping of the slabs together prevents to a considerable degree any flowing vertically), if

it is prevented from flowing horizontally by links connecting the rods, occasionally such links will be overtaxed and will break. It was found that this was occurring with the Lyons type of fender, and, moreover, that such broken links would not be discovered immediately, and would themselves tend to destroy the slabs adjacent them, and that the fender would thus disintegrate from within, within a short period of time. It is, therefore, one of the essential distinctions of the present invention that the rods 2 be completely unconnected except as they are connected by the slabs themselves.

Thus connected, when the fender is compressed between the stem of the tug which carries it and a barge or pile, the compression is generally along a vertical line, parallel to the rods, and intermediate two rods. The rubber composition, compressed thus, tends to flow horizontally. The rods separate somewhat, as they could not if their separation was restrained by links, but immediately upon removal of the compressive force the resilience of the rubber restores the rods to their former relationship and spacing.

It should be pointed out here that while the rods are relatively stiff and inflexible, this quality is not essential, for cables may be substituted for the rods, such cables having limited flexibility, and indeed, this might be a desirable substitution in view of the fact that the fenders can then adjust themselves slightly better to surface irregularities of the vessel whereon they are mounted.

The fender might be supported in any convenient manner; for instance, if the fender were made sufficiently strong or were sufficiently light, it might be supported by a link embedded between two courses, encircling the rearmost rod, and projecting outwardly of the fender for engagement by a suitable supporting cable or the like. However, such fenders are usually too heavy and the rubber has not sufficient strength to enable the entire fender to be supported in this fashion. It is therefore preferable to support the fender by a cable which more or less encircles the fender as a whole, and which draws it rearwardly to points of securement aft of the ends of the wing. Thus the support might be a cable which is wholly separate from the fender, or such a cable might be merely embedded somewhat in the softer rubber of the fender's outer wearing surface, and then led aft. On the other hand, and preferably, the support is in the nature of a cable or the like, which is embedded between courses, which engages certain or all of the rods 2, but which is not connected to any of the rods, or at least to not more than one such rod, for instance that one which is centrally located in the pudding, and from this single point of securement the cable 5 is led aft, through each of the wings, either outside of all the rods 2 or interwoven between the rods. If interwoven between the rods, in order to avoid binding it is preferable that the rods be somewhat staggered in position, so that the cable is kept, as nearly as may be, straight, in order that it will not bind, and in order that the rods may separate under compressive stress, without appreciable resistance thereto arising by reason of the cable. At its ends the cable 5 projects outside the fender, and may be formed in a loop 6 for securement of an eye 8 or a similar means at the end of a cable 7, the latter of which is suitably secured on deck or at the rail.

The fender shown in Figures 1, 2, and 3 has a

tier of slabs extending transversely between the wing tiers at the apex of the V fender to form a pudding which is not appreciably thicker than the wings. If a thicker pudding is desired, however, the same principles of construction may be employed to extend the pudding forwardly, slabs 10 being laid fore and aft ahead of the wings, and connected crosswise by a further tier of transverse slabs 9, in the manner illustrated in Figure 4. An extra wide slab in occasional courses may overlie the slabs 1 and 9, both.

No particular pattern need be followed in laying up the slabs in courses. It is only sufficient that they be laid in such a manner that the fender is reasonably solid throughout, and that there are sufficient slabs connecting adjoining but spaced rods to form of the fender an integral whole.

What I claim as my invention is:

1. A marine fender comprising a plurality of approximately flat pieces of tire casing material of appreciable width and length laid in face-to-face relationship, and in coplanar substantially end abutting relationship, in the form of a substantially imperforate, solid fender wherein stresses are transmitted from one piece to the adjoining pieces, and wherein the opposite edges of the pieces define the inner and outer wear surfaces of the fender, and tension members extending transversely through the individual pieces, and hence through the fender, generally parallel to its wear surfaces, the several tension members being yieldingly connected to each other solely by the tire casing pieces themselves.

2. A marine fender comprising a plurality of approximately flat pieces of tire casing material of appreciable width and length, laid in horizontal courses in face-to-face relationship, and in coplanar substantially end abutting relationship, in the form of a fender wherein the opposite edges of the pieces define the inner and outer wear surfaces of the fender, tension members extending through the individual pieces, and hence through the fender generally parallel to its wear surfaces, means upon the tension members to hold the pieces tightly together and to prevent appreciable deformation of the fender in a vertical direction, and means to support the fender in operative position comprising a further tension member extending transversely of said first tension members between their ends and engaged with at least one thereof, and embedded between two courses.

3. A marine fender comprising a plurality of approximately flat slabs of tire casing material laid up in broken horizontal courses in face-to-face and coplanar end abutting relationship, in the form of a fender the inner and outer wear surfaces whereof are defined by the exposed edges of the slabs, spaced rods extending vertically through the slabs, at intervals, and yieldingly interconnected solely by the slabs themselves, means upon the rods to clamp the slabs tightly together, and to prevent appreciable deformation of the fender in a vertical direction, and a cable encircling the fender and engaged

with certain of said rods, and extending outwardly of the fender as a support for the fender.

4. A marine fender consisting of a plurality of rods spaced apart, a plurality of flat slabs of tire casing material, each of a length to include a plurality of rods, and to constitute the sole connection between the rods, but each of insufficient length to include the entire set of rods, said slabs being threaded upon the rods in face-to-face and coplanar substantially end abutting relationship, to constitute a substantially imperforate and solid fender of a desired shape, means to hold the slabs thus against appreciable separation lengthwise of the rods, while leaving the fender free to yield transversely of the rods to the extent permitted by the slabs themselves, and means engaged with selected rods only for supporting the fender.

5. A marine fender consisting of a plurality of rods spaced apart, a plurality of flat slabs of tire casing material, each of a length to include a plurality of rods, and to constitute the sole connection between the rods, but each of insufficient length to include the entire set of rods, said slabs being threaded upon the rods in face-to-face and coplanar substantially end abutting relationship, to constitute a substantially imperforate and solid fender of a desired shape, and a cable embedded within the fender, between two courses of slabs, engaged with the outer faces of, but not connected to, certain rods, and encircling the fender, the cable having ends projecting from the fender adjacent the latter's ends, for supporting engagement.

6. A marine fender comprising a plurality of slabs of tire casing material laid up in horizontal courses in face to face relationship in the form of a fender, the inner and outer wear surfaces whereof are defined by the exposed edges of the slabs, a plurality of rods extending vertically through the slabs, and disposed in staggered spaced relationship, means upon the rods to clamp the slabs tightly together, and a cable extending horizontally through the fender embedded between adjacent courses of said slabs, interwoven between the staggered rods to lie substantially parallel to the wear surfaces of the fender, and projecting beyond the ends of the fender for engagement to support the fender.

7. A marine fender comprising a plurality of slabs of tire casing material laid up in horizontal courses in face to face relationship in the form of a fender of V shape, the outer and inner wear surfaces whereof are defined by the exposed edges of the slabs, and including a tier of slabs extending transversely between the adjacent ends of the fender wings at the apex of the V fender, a second tier of transverse slabs parallel and adjacent to said first tier and on the side thereof opposite the fender wings, slabs of tire casing material interlaid with and extending between said two tiers of transverse slabs, and spaced rods extending vertically through each of the tiers of transverse slabs and through the interlaid interconnecting slabs to hold all such slabs in stacked position.

HARRY W. BELL.
